UNITED STATES PATENT OFFICE.

GEORGE T. THOMAYER, OF ALBANY, NEW YORK, ASSIGNOR, BY MESNE ASSIGNMENTS,
TO ECONOMY DYEING MACHINE CORPORATION, OF ALBANY, NEW YORK, A COR-
PORATION OF NEW YORK.

YARN-DYEING DEVICE.

Application filed October 17, 1924. Serial No. 744,098.

To all whom it may concern:

Be it known that I, GEORGE T. THOMAYER, a citizen of the United States, and a resident of Albany, county of Albany, State of New York, have invented certain new and useful Improvements in Yarn-Dyeing Devices, of which the following is a specification.

This invention relates to improvements in dye tanks, more especially to those types of tanks in which a passing yarn is dropped at intermittent intervals onto a dye applying wheel and, relates more particularly to a construction of tank giving ready access to the interior of the tank and to its operating mechanism to facilitate its cleaning.

In tanks of this general type as heretofore constructed, the shaft carrying the dye applying wheels has been mounted in the body of the tank and has not been readily removable, if at all, without emptying and dismantling the tank and its associated mechanism after the cover has been removed. It has accordingly been difficult to give the interior of these tanks and the dye wheels a thorough cleaning.

An object of my present invention is to provide a dye tank construction which will enable the dye wheels and their shaft to be removed with the removal of the cover of the tank to render all of the mechanism in the interior of the tank readily accessible.

Another object of the invention is to provide a tank having a removable cover and a dye wheel shaft mounted on said cover independently of said tank and removable from said tank on the removal of the cover without distributing the contents of the tank.

A further object of the invention is to provide a tank and cover construction and arrangement that will protect the yarn from contacting with the dye wheel and thus getting streaked with dye during the removal of the cover and to provide a dye tank in which the level of dye liquor may be easily and accurately adjusted and in which leakage through the splashing of dye is avoided.

With these and other objects in view, which will appear from the following description, the invention comprises the tank and associated mechanism described and set

forth in the following specification and claims.

The various features of the invention are illustrated in the accompanying drawings, in which:

Fig. 1 is a cross sectional view of the tank.

Fig. 2 is a vertical, longitudinal, sectional view of the tank shown in Fig. 1, and

Fig. 3 is a plan view of a tank embodying a preferred form of my invention.

In my present invention, an elongated tank for holding the dye liquor, and adapted to be mounted in proper position on a winding machine, is provided with a cover having a series of openings or slots spaced longitudinally in position to underlie the passing yarns and, supported from the cover within the tank, is a longitudinal shaft having dye applying wheels spaced on said shaft to project through said slots. The mounting of the shaft on the cover is such as to be independent of any supports in the tank so that upon lifting the cover, the dye wheel shaft and dye wheels mounted thereon are lifted clear of the interior of the tank and of the dye liquor to expose all portions of the shaft and wheels for cleaning. The randoming mechanism for tossing or lifting the passing yarn and permitting it to fall back onto the dye wheels at intervals is preferably mounted on the exterior of the tank in the usual manner so that the cover and its dye wheel supports may be removed without disturbing the yarn, special means being provided to keep the yarn from the dye wheels during the removal of the cover.

Referring more particularly to the accompanying drawings, a tank 10 of any suitable length is provided at its upper edges with projecting supporting flanges 11 on which rests an upwardly curved or arched cover 12 having outwardly projecting supporting flanges 13, resting on and secured to the flanges 11. In the upper surface of the cover 12 one or more transverse slots or openings 14 are spaced at intervals to correspond with the positions of the yarn to be dyed, and projecting into these slots 14 are dye applying surfaces of wheels 15 mounted on a shaft 16 extending longitudinally in the tank in position to bring the

upper dye applying surfaces of the wheels 15 slightly above the upper edges of the openings 14 and with their lower edges dipping into a body of dye liquor 17 in the 5 tank 10.

The shaft 16 is rotatably mounted from the cover 12, and independently of the tank 10, by means of bearings 18 having outwardly projecting lugs 19 which are secured to 10 the inner surface of the cover 12 by means of screws 20, so that, when the cover 12 is lifted the bearings 18, shaft 16, and dye wheels 15 are lifted therewith leaving the 15 interior of the tank free of any of the dye mechanism and leaving the dye wheels and supporting shaft exposed and accessible for cleaning or other purposes. The upper end edges of the tank 10 may be notched to enable the shaft 16 to project through the ends 20 of the tank and to be readily lifted therefrom. On the projecting end of the shaft 16 is mounted a suitable driving wheel or pulley or other driving means (not shown in the drawings) and on this portion of the 25 shaft may also be mounted a notched or saw toothed wheel 21 for actuating the yarn tossing or randomizing devices.

The yarn, in passing over the dye wheels 15 is guided between guide wheels 22 and porcelain eyelets 23' on opposite sides of the tank and dye wheels. The guide wheels 22 are preferably supported from the tank by means of brackets 23 projecting upwardly and outwardly from a side wall of the tank 30 to a suitable height and may be provided with suitable tensioning springs 25. With this arrangement, the yarn 26 may be supported in position on the winding and dyeing machine on which the tank may be mounted, while the cover 12 is removed, the dye wheels 15 cleaned, and the cover replaced without disturbing the yarn. The porcelain guiding eyelets 23 may be mounted on the cover supporting flange 13 at the 35 opposite side of the tank, the yarn being disengaged from these eyelets before the cover is removed.

To prevent the yarn from sliding along the exposed surface of the dye wheels as 40 the cover 12 is lifted and slid from position as it is being removed, upwardly projecting yarn guides 27 are mounted on the cover at positions slightly spaced sidewise of the 45 openings 14 so that, prior to removing the cover, the yarn 26 may be lifted over the guides to the positions indicated in broken lines in Fig. 3 to hold them free of the exposed surfaces of the dye wheels. When the 50 yarn has been lifted over these guides, it is kept free of the dye applying wheels 15 regardless of any movement or positioning of the cover 12.

Any suitable type of yarn tossing or lifting device may be employed on the tank. 55 The type shown in the drawings is, however,

preferred. This device comprises a finger 28 of a bent hair pin form having a bridge portion 29 in alignment with the guide wheels 22 and eyelets 23' and is mounted on a rock shaft 30 extending lengthwise at 70 one side of the tank 10. The rock shaft 30 is rocked by means of an arm 31 projecting towards the wheel 21 and having a longitudinal slot 32 therein in which a pin 33 is mounted at an adjustable distance from the axis of the shaft to ride over the teeth of the wheel 21 and thus impart a rocking movement to the shaft 30. A tensioning spring 34 is provided between the arm 31 and the side wall of the tank 10 to hold the pin in close contact with the periphery of the wheel 21. By adjusting the distance of the pin 33 in the slot 32 from the axis of the shaft 30, the position of the lifting finger 28 may be adjusted. The rock shaft 30 is supported on brackets 33 projecting sidewise from the side of the tank 10 and may be rotated to swing the fingers 28 (one for each dye wheel) out of position after the yarn 80 has been lifted over the guide pins 27 to enable the cover 12 to be easily lifted from the tank 10.

A fresh supply of dye liquor and a constant level of liquor may be maintained in the tank 10 by supplying a constant stream 95 of the liquor through a supply pipe 35 at one end of the tank and permitting a constant overflow through an overflow pipe 36, which telescopes into an outlet pipe 37. To provide a uniform overflow action the upper open end of the overflow pipe 36 is beveled as at 38 and the height of the overflow opening may be adjusted by sliding the pipe upwardly or downwardly in the outlet pipe 37 a rod 39 extending upwardly from the overflow pipe through the cover 19 the upper 100 end of which is threaded and provided with a nut 40 to hold the pipe at any desired height. To intercept the spray from the dye liquor due to the agitation by the 105 wheels 15, the side flanges 13 of the cover are turned inwardly as at 41 and downwardly as at 42 to provide a spray intercepting curtain.

With the above construction the tank 110 cover 12 may be lifted from the tank 10, upon loosening its flange 13 from the flange 11 without disturbing any of the other mechanism of the tank, and upon removal of the cover the dye wheels 15 are completely 115 exposed to view and to ready access. With this construction, also as the dye wheels are removed with the cover, there is no danger of the yarn resting against the dye 120 wheels and getting saturated with the dye 125 upon the removal of the cover.

As changes of construction could be made within the scope of my invention, it is intended that all matter contained in the 130 above description or shown in the accom-

panying drawing shall be interpreted as illustrative and not in a limiting sense.

Having described the invention, what I claim and desire to secure by Letters Patent is:

1. Apparatus of the type described which comprises, a dye tank, a cover for said tank, said cover having an opening therein, a power shaft means mounted from said 10 cover to support the power shaft, a dye wheel on said shaft projecting into said opening, the cover, supporting means, power shaft and dye wheel being removable as a structure from said tank.
- 15 2. Apparatus of the type described which comprises, an elongated dye tank, a cover for said tank, said cover having a series of longitudinal spaced openings therein, a shaft mounted longitudinally in said tank 20 from said cover and removable therewith, and a series of dye wheels on said shaft spaced to project into said openings in said cover.
- 25 3. Apparatus of the type described which comprises, an elongated dye tank, a cover for said tank, said cover having a series of longitudinal spaced openings therein, bearings mounted to depend downwardly from said cover into said tank, a shaft mounted 30 longitudinally in said tank in said bearings, and a series of dye wheels on said shaft spaced to project into said openings in said cover.
- 35 4. Apparatus of the type described which comprises, an elongated dye tank, a cover

for said tank, said cover having a series of longitudinally spaced openings therein, a shaft mounted longitudinally in said tank from said cover and removable therewith, guide pins on said cover spaced to one side 40 of their respective openings, and a series of dye wheels on said shaft spaced to project into said openings in said cover.

5. Apparatus of the type described which comprises, a dye tank, a cover for said 45 tank, said cover having a series of longitudinally spaced openings therein, bearings mounted to depend from said cover into said tank, a shaft mounted in said bearings longitudinally of said openings, a series of dye 50 wheels on said shaft spaced to project into said openings in said cover, and guide pins projecting upwardly from said cover spaced to one side of their respective openings.

6. Apparatus of the type described which comprises, a dye tank, a cover for said tank, said cover having an opening therein bearings depending from said cover, a shaft mounted in said bearing below said opening, a dye applying wheel mounted on said 60 shaft to project into said opening, a guide pin projecting upwardly from said cover at one side of said opening, a yarn guiding means mounted on one side of said tank in alignment with said opening, a rock shaft 65 mounted on one side of said tank, a yarn tossing finger mounted on said rock shaft in alignment with said opening, and means for giving said rock shaft a rocking motion.

GEORGE T. THOMAYER.
